UNITED STATES PATENT OFFICE.

RHODOM M. BROOKS AND JAMES M. BROOKS, OF JENKINSVILLE, ASSIGNEES
OF ONE-THIRD TO M. L. BATES AND JOHN M. WILLIAMS, OF GRIFFIN, GA.

CAR-COUPLING.

SPECIFICATION forming part of Letters Patent No. 255,072, dated March 14, 1882.

Application filed January 30, 1882. (No model.)

To all whom it may concern:

Be it known that we, RHODOM M. BROOKS and JAMES M. BROOKS, of Jenkinsville, in the county of Pike, and in the State of Georgia, have invented certain new and useful Improvements in Car-Couplings; and we do hereby declare that the following is a full, clear, and exact description thereof, reference being had to the accompanying drawing, and to the letters of reference marked thereon, making a part of this specification.

This invention relates to certain improvements in car-couplers; and it has for its object to provide suitable means whereby the link may be held in position for coupling and the pin automatically dropped through the link to couple the cars, as more fully hereinafter specified. These objects we attain by the apparatus and mechanism illustrated in the accompanying drawing, in which is represented a longitudinal sectional view of our invention.

The letter A indicates the draw-heads of our improved car-coupler, which are identical in construction. The said draw-heads are each provided with a circular flaring opening, B, in front, to guide the link through the aperture C, behind which the pin is adapted to fall through the vertical openings D. The draw-heads are recessed below, as indicated by the letter E, and in the said recesses are fulcrumed the segmental levers F, as indicated. These levers are weighted at their lower ends, so that when in a normal position the upper end of each will fall under the upper hole, through which the coupling-pin is inserted, and support the pin in position to be dropped through the link, the said lever by the insertion of the link being thrown back so as to permit the pin to drop. The upper end of the lever is provided with a shoulder, G, which holds the link horizontally, so that it will properly enter the opposite coupling-head. The lower end of the

lever is provided with a vertical aperture, H, into which the lower end of the pin is adapted to pass when the cars have been coupled, so as to release the shoulder from the link and allow the same to play freely without wear. By means of the circular flaring opening in the draw-heads the link is guided into the same, if the draw-head should be slightly out of line, and is permitted to move freely in all directions to accommodate itself to the motion of the cars. The weight of the pin, when resting upon the lower end of the lever, will assist to hold the lever in position until thrown back by the link when the cars come together and are coupled, the pin by the act of coupling being dropped into the aperture in the lower end of the lever, as before mentioned.

It is evident that a car provided with our coupling device can be employed and coupled with a car provided with the ordinary bumpers, and is thus adapted to be used with the rolling-stock common to all railroads. If the cars should be of different heights, the coupling can be effected by using a bent coupling-link.

Having thus fully described our invention, what we claim, and desire to secure by Letters Patent, is—

In combination with the shouldered and weighted lever fulcrumed in the draw-head, the coupling pin and link, the lever being provided with an aperture at its lower end, to be engaged by the pin so as to hold the lever back and keep the shoulder away from the link, substantially as specified.

In testimony whereof we affix our signatures, in presence of two witnesses, this 28th day of January, 1882.

R. M. BROOKS.
JAMES M. BROOKS.
